UNITED STATES PATENT OFFICE.

M. FRED. BELL, OF FULTON, MISSOURI.

ADJUSTABLE CHAIR.

SPECIFICATION forming part of Letters Patent No. 226,475, dated April 13, 1880.

Application filed October 23, 1879.

To all whom it may concern:

Be it known that I, M. FRED. BELL, of Fulton, in the county of Callaway and State of Missouri, have invented certain new and useful Improvements in Adjustable Chairs; and I do hereby declare that the following is a full, clear, and exact description of the invention, which will enable others skilled in the art to which it appertains to make and use the same, reference being had to the accompanying drawings, which form a part of this specification, and in which—

Figure 1 is a perspective view. Fig. 2 is a vertical section. Fig. 3 is a rear elevation, and Fig. 4 is a plan of the under side of the adjustable seat.

Similar letters of reference indicate corresponding parts in all the figures.

This invention has relation to adjustable chairs; and it consists in the improvements hereinafter more fully set forth, and particularly pointed out in the claims.

In the drawings, in which I have shown this invention as applied to a rocker, A designates the legs, and B the arms or side pieces, of the chair-frame. The back consists of two side pieces, C C, which are pivoted at c c in the rear ends of arms B B, and united at the top by a cross-piece, C'. To the lower ends of the back-pieces C C are pivoted two arms, D D, which extend forward, resting upon a rod, E E', and are at their forward ends pivoted upon opposite sides of the seat-piece F. About midway upon the under side of the solid seat-piece F is hinged a rearwardly-projecting arm, G, which is inserted through the two arms h h of a hollow cross-shaped casting, H. The other arms, h' h', of this casting are screw-threaded, the rod-section E being inserted 40 permanently into one of them, while the opposite section, E', is inserted into the other. The screw-threaded end of the part E' projects sufficiently far into the cross H to bear against the hinged arm G, and is operated by 45 a knob or thumb-screw, g. It follows that by turning this knob to one side the rod E' will bind arm G in the cross H, while by turning it in the opposite direction arm G is released and may be adjusted within said cross H.

The back and bottom proper, denoted by the letter I, is flexible and in one piece, so that it will readily adjust itself to the figure and position of the person occupying the chair. It consists of a series of slats, i i i, the ends of which are interwoven with thin flexible metal strips k k k. These strips may be formed by splitting a band, l, of thin sheet metal into three narrow strips, and by then fastening the solid part l of the band upon the back part of the cross-piece C' and interweaving each end of the slats i between the split strips k k k, in the manner clearly shown in the drawings, a very strong, durable, and flexible seat is formed, the opposite or lower ends of the strips k being secured upon the under side of the solid seat-piece F.

It is obvious, however, that, if desired, a flexible seat of a different construction may be used, and also that a flexible seat and back constructed as herein described may be used with a chair-frame of a different construction; but I prefer to combine the two in the manner described, as by this means I produce a very strong, durable, and convenient chair at a small expense.

It will be observed that the adjustment of the seat-frame D D F and back-frame C C C' is independent of the side pieces, B B, and feet A A, the adjustment being effected by means of the pivoted arm G, cross H, and adjustable rod E'. Hence, whatever may be the position of the seat and back, the relative position to these of the legs and arms remains unchanged, so that there is not, as in most adjustable chairs, any danger of the chair accidentally breaking down, nor can the adjustment, after being once effected, be changed except by operating the screw-rod E'.

Having thus described my invention, I claim and desire to secure by Letters Patent of the United States—

1. The combination, with the permanent sides B B and adjusting device consisting of the cross H and rods E E', of the pivoted back-frame C C C' and pivoted seat-frame D D F, provided with the hinged arm G, substantially as and for the purpose herein shown and described.

2. The adjustable chair herein shown and described, consisting of the pivoted back-frame C C C' and pivoted seat-frame D D F, flexible fabric I, suspended between said pivoted back and seat frames, adjusting device composed of the rods E E' and cross H, in combination with the hinged arm G and permanent side pieces B B, having the feet or supports A A, all constructed and combined to operate sub-

stantially in the manner and for the purpose to herein shown and described.

In testimony that I claim the foregoing as my own I have hereto affixed my signature in presence of two witnesses.

M. FRED. BELL.
